UNITED STATES PATENT OFFICE.

ROSS F. MAHER, OF ST. PAUL, MINNESOTA.

DESIGN FOR A BILLIARD-CUE RACK.

46,600.

Specification for Design.

Patented Oct. 27, 1914.

Application filed August 13, 1914. Serial No. 856,693. Term of patent 7 years.

To all whom it may concern:

Be it known that I, Ross F. MAHER, a citizen of the United States, residing in the city of St. Paul, county of Ramsey, and State of Minnesota, have invented a new, original, and ornamental Design for Billiard-Cue Racks, of which the following is a specification, reference being had to the accompanying drawing, forming part thereof.

The figure is a perspective view of a billiard cue rack, showing my new design.

I claim:

The ornamental design for billiard cue racks, as shown.

ROSS F. MAHER.
